G. P. HELFRICH

FOUNTAIN ATTACHMENT FOR BRUSHES

Filed May 31, 1922

INVENTOR.
GEORGE P. HELFRICH

BY

Bradley L. Benson

ATTORNEY.

UNITED STATES PATENT OFFICE.

GEORGE P. HELFRICH, OF SAN FRANCISCO, CALIFORNIA.

FOUNTAIN ATTACHMENT FOR BRUSHES.

Application filed May 31, 1922. Serial No. 564,786.

To all whom it may concern:

Be it known that I, GEORGE P. HELFRICH, a citizen of the United States of America, residing at 902 Steiner Street, San Francisco, in the county of San Francisco and State of California, have invented certain new and useful Improvements in Fountain Attachments for Brushes, of which the following is a specification.

10 The present invention is an improved fountain attachment for brushes and relates to means for continuously or intermittently supplying a brush, such as a flat paint brush, with fluid to be applied or distributed 15 through the brush.

The objects of the invention include:

(1) The provision of a liquid container provided with means whereby it can be readily removably engaged on a common brush, 20 and in effect become a part thereof, in which position it will supply the brush with paint or the like by a simple finger and thumb manipulation.

(2) The provision of a device of character described, which will render it unnecessary for a painter to frequently dip and wipe the brush in a bucket, which operations cause a waste of time and material.

(3) The provision of means whereby a brush may be supplied with a sufficient quantity of paint to cover a considerable area, and thus enable a painter working on a ladder or other inconvenient place to save time and labor in his occupation.

35 In this specification and the annexed drawings, the invention is illustrated in the form considered to be the best, but it is to be understood that the invention is not limited to such form, because it may be embodied in other forms, and it is also to be understood that in and by the claim following the description it is desired to cover the invention in whatever form it may be embodied.

45 In the accompanying 1 sheet of diagrams: Fig. 1 is an elevation of my device, showing the side thereof adapted to engage the brush, the brush being indicated in dotted lines.

50 Fig. 2 is a section of Fig. 1 taken on the line II—II.

Fig. 3 is a side elevation of Fig. 1.

Fig. 4 is a section of Fig. 1 taken on line IV—IV.

Fig. 5 is a perspective view illustrating 55 the mode of operation of my device.

Referring to the diagrams: The numeral 1 indicates a liquid container or fountain here shown as rectangular in form and provided with a cover 2 hinged at 3. The cover, on the inside, is provided with a rubber gasket 4 to prevent leakage and is also provided with a spring latch 6 adapted to engage (in closed position) a lug 7 on the container 1.

The lower end of container 1 is curved inwardly at the bottom, as shown at 8, where it terminates in a restricted discharged orifice 9, which is so positioned that when the device is clamped to a brush 11 the liquid leaving orifice 9 will enter the bristles of the brush from the side and at a point near the handle.

The orifice 9 is controlled by a slide or closure 12, slideable vertically between the wall of the container and a yoke or band 13 which overlies the container and engages the sides thereof.

The slide 12 is provided with upturned ears 13^a, which afford convenient means for 80 sliding the closure to open or closed position.

To conveniently clamp the fountain to a brush, I provide the following means: At 14 I show a bridge member, through the U-shaped portion of which extends a pin 16. 85 Pivotally mounted on this pin and in eccentric relation thereto is a cylindrical member 17 from which extends a tongue or handle 18.

When this handle is rotated to open position the eccentrically mounted member 17 is in a position to clear the handle of a brush extended under the bridge 14, and when the handle is in the full line position shown in Fig. 2 the said member engages the brush and forces it against upstanding sharp pointed studs 10 and thus lock the brush to the container.

When the device is thus engaged with a brush, it overlies the brush and the combination may be grasped and manipulated between the thumb 21 and fingers 22 in the usual manner.

In operation, if more paint is required, a slight pressure exerted by the fingers 22 105 will depress the outer wall of the container 1 and liquid will be forced into the bristles through orifice 9. In finishing off or other

operations requiring no replenishment of paint the thumb 21 manipulates the ears 13^a and closes orifice 9.

I claim:

- 5 1. A fountain attachment for flat paint brushes and the like comprising a relatively flat liquid container adapted to overlie a brush, a bridge member on said container, a tongue member eccentrically mounted in 10 said bridge member and adapted, when rotated to secure and engage a brush between said bridge and said container, and studs upstanding on said container so positioned

as to penetrate said brush when so engaged.

2. A fountain for brushes comprising a 15 flat liquid container, clamping means carried by said container for removably engaging a brush, a tapered portion on said container terminating in a discharge orifice adapted, when pressure is applied to the 20 walls of the container, to discharge liquid against the side of the brush so engaged, and a closure for said orifice slidable to open and closed positions.

In testimony whereof I affix my signature.

GEORGE P. HELFRICH.
